[57] **CLAIM**

The ornamental design for a ticket holder device, as shown and described.

DESCRIPTION

FIG. 1 is an elevational view of the front plate of the subject ticket holder device illustrating its ornamental design; FIG. 2 is an elevational view of the right side of the ticket holder device with the front plate facing upwardly; FIG. 3 is an elevational view of the rear plate of the subject ticket holder device; FIG. 4 is an elevational view of the left side of the ticket holder device with the rear plate facing upwardly; FIG. 5 is an elevational view of the top of the ticket holder device with the front plate facing upwardly; FIG. 6 is an elevational view of the bottom of the subject ticket holder device with the front plate facing upwardly; and,

FIG. 7 is a front elevational view of the subject ticket holder device illustrating the placement of a ticket within the device.

The broken line showing of a ticket in FIG. 7 is for illustrative purposes only and forms no part of the claimed design.
